United States Patent Office

Des. 183,241

Patented July 22, 1958

183,241

ARMCHAIR

Morton R. Cohen, Chicago, Ill.

Application February 12, 1958, Serial No. 49,616

Term of patent 14 years

(Cl. D15—1)

Fig. 1 is a rear perspective view of an armchair, showing my new design;

Fig. 2 is a front perspective view of the same; and

Fig. 3 is a side elevational view of the same.

I claim:

The ornamental design for an armchair, substantially as shown.
